PHONOGRAPH

Carl G. Johnson and James A. Boyajian, Chicago,
Ill., assignors to J. P. Seeburg Corporation, Chi-
cago, Ill., a corporation of Illinois

Application May 8, 1941, Serial No. 392,420

17 Claims.

(Cl. 274—10)

This invention relates to phonographs and has for one of its objects to provide a simple phonograph in which the manipulations of the player arm are effected automatically.

A further object of the invention is to provide such a phonograph which is adapted to play records of a plurality of sizes and to provide a simple manual control for setting the phonograph for automatically playing a record of any particular size.

A further object of the invention is to provide a phonograph having a manually operable switch and automatic means for moving the player arm clear of the record and for opening the switch.

A further object of the invention is to provide a phonograph having an automatic brake, manual means for releasing the brake, and automatic means for moving the player arm clear of a record and for applying the brake at the end of the playing of the record.

A further object of the invention is to provide a phonograph having an idler adapted to engage driving and driven elements, manual means for connecting the idler to said elements and automatic means for moving the idler out of engagement with said elements at the end of the playing of a record.

A further object of the invention is to provide an automatic phonograph having a control switch and a player arm, power means for driving the turntable and manipulating the player arm, and automatic means for moving the player arm clear of the record and opening said switch at the end of the playing of a record.

Other objects, advantages and capabilities of the invention will appear from the following description of a preferred embodiment thereof taken in conjunction with the accompanying drawings, in which:

Fig. 1 is a plan view of our improved phonograph;

Fig. 2 is a similar view, the turntable being almost completely broken away to show mechanism located beneath the turntable and the motor board;

Fig. 3 is an elevational view of the phonograph as viewed from the right in Fig. 2;

Fig. 4 is an inverted plan of the phonograph on a larger scale and partly broken away, showing the mechanism in the "off" position;

Fig. 5 is a similar view showing the mechanism in the "on" position and beginning to play a record of smaller size;

Fig. 6 is a sectional plan view of the mechanism taken on the line 6—6 of Fig. 3, the mechanism being in "off" position corresponding to Fig. 4;

Fig. 7 is a fragmentary sectional plan view taken on the line 7—7 of Fig. 3, the elements

shown therein being in "off" position corresponding to Figs. 4 and 6;

Fig. 8 is a sectional plan view similar to Fig. 6 showing the mechanism in "on" position corresponding to Fig. 5, the phonograph beginning to play a record of smaller size;

Fig. 9 is a sectional plan view similar to Fig. 7, showing the mechanism in the "on" or playing condition;

Fig. 10 is a view similar to Figs. 7 and 9, showing an intermediate condition of the mechanism, that being the relation of elements during the actuation of the manual control and before the switch is closed; and

Fig. 11 is a perspective view of elements in the "off" position corresponding to Figs. 4 and 7.

Referring to the drawings, the phonograph comprises a motor board 10 on the under side of which is mounted a bracket 11. The bracket 11 provides a suitable support for a turntable spindle 12 which projects upwardly through the motor board 10. On the upper side of the motor board the spindle 12 has mounted thereon a turntable 13. The spindle 12 is connected to the turntable 13 so that they both rotate together.

The lower portion of the spindle 12 has rigidly mounted thereon a pinion 14 which is adapted to mesh with the peripheral teeth on a mutilated gear 15. The mutilated gear is mounted for free rotation upon a shaft 16 carried between the bracket 11 and the motor board 10.

Below its teeth, the pinion 14 carries a plurality of large teeth 17 which project outwardly in the radial direction. As will hereinafter be explained, the gear 15 is given two movements constituting one complete revolution between the playing of records. During the playing of a record, a gap 18 in the peripheral teeth of the gear 15 is opposite the pinion 14 so that the gear 15 is at rest during the playing of a record. At this time a detent 19 is forced by a spring 20 into a small recess 21 on a flange of the gear 15 above its teeth so that the gear is held against displacement due to vibration or other accidental causes.

The phonograph is actuated by means of an electric motor 22 which has a small driving wheel 23 located on the upper side of the motor board 10. An idler 24 is adapted to engage the driving wheel 23 and the inner side of the flange 25 of the turntable 13. The idler 24 is mounted on an arm 26 pivotally mounted on the motor board at 27. A spring 28 connected to the arm 26 and to the motor board 10 biases the idler 24 towards engagement with the driving wheel 23 and the flange 25.

The idler 24 is preferably provided with a tire 29 of rubber or other suitable plastic material. When the turntable is not being driven, the idler 24 is held out of engagement with the wheel 23

and flange 25 so that there is no possibility of flat surfaces being produced on the tire 29.

The arm 26 rigidly carries an extension 30 which is connected by a tension rod 31 to one end of a lever 32 pivotally mounted on the upper side of the motor board on stud 33. This end of the lever 32 has a surface 34 adapted to be engaged by a tooth 35 of a pawl 36. The pawl 36 is pivotally mounted on the upper surface of the motor board 10 by means of a stud 37.

The pawl 36 rigidly carries an arm 38 having a braking member 39 which is adapted to engage the inner side of the flange 25 of the turntable 13. The arm 38 is preferably adjustably mounted on the pawl 36 so that correct adjustment of the braking member may readily be made.

The aforesaid end of the lever 32 and the pawl 36 are biased towards each other by means of a spring 40. This spring biases the pawl 36 so that the braking member 39 tends to engage the turntable, and the spring also biases the rod 31 towards the idler 24 so that the idler may be engaged with the wheel 23 and the flange 25 by the spring 28.

When the tooth 35 is in engagement with the surface 34, the braking member 39 is in engagement with the flange 25 and the idler 24 is held away from the wheel 23 and flange 25, as shown in Fig. 7. When, however, the pawl 36 is swung in clockwise direction as viewed from above, the tooth 35 is swung away from the surface 34 and the combined action of the springs 40 and 28 effects engagement of the idler 24 with the wheel 23 and flange 25, as shown in Fig. 9.

When the phonograph is not operating, the braking member 39 is forced against the flange 25 of the turntable by the spring 40, as shown in Fig. 7, and the lever 32 has its surface 34 bearing against the tooth 35 of the pawl 36 in a substantially radial direction by the same spring 40. In this position of the lever 32, the rod 31 holds the idler 29 clear of both the flange 25 and the driving wheel 23. It will of course be understood that instead of the common spring 40, two separate springs may be provided for the pawl 36 and the lever 32 so as to bias them in the same effective directions as does the spring 40.

The player arm 43 is connected by a horizontal pivot 44 adjacent its rear end to an arm 45 which is rigidly mounted on the upper end of a vertical sleeve 46. The sleeve 46 is pivotally mounted on a pedestal 47 so as to provide for the free translational movement of the player arm over the record.

A rod 48 is located in the sleeve 46 for free vertical movement. The upper end of the rod 48 is adapted to engage the under side of the player arm 43 at a position slightly forward of the pivot 44. It will readily be understood that when the rod 48 is moved upwardly, the player arm 43 is elevated from its normal substantially horizontal position.

The lower end of the rod 48 rides on a cam 49 formed on the upper side of the gear 15. The cam 49 is provided with a cam rise 50 which raises the pin 48 immediately after the playing of a record, and a cam fall 50' which permits the pin 48 to move downwardly again at the proper time to bring the player arm needle into engagement with the record.

On the lower end of the sleeve 46 is rigidly mounted a horizontal arm 51 which carries at its outer end a pin 52 which projects both upwardly and downwardly from the arm 51. The lower end of the pin 52 rides in a cam track 53 formed in

the upper surface of the cam wheel 15. During the playing, the pin 52 is clear of the inner cam member 54 which defines one side of the track 53 so that the player arm is free to move inwardly during playing of the record, as shown in Fig. 8.

After the playing of the record, the cam wheel 15 starts to rotate in the counter-clockwise direction as viewed from above, from its position in Fig. 8, and the pin 52 is engaged by a cam rise 55 on the inner cam member 54 so that the pin 52 is moved outwardly and consequently the player arm is thrown outwardly clear of the record. The player arm remains in its outward position during the time that the pin 52 is located in the cam track 53.

When the pin 52 is thus thrown out, its upper end engages an arm 56 which is pivotally mounted by means of a stud 57 on the under side of the motor board 10 so that this arm is likewise thrown out into its position in Fig. 6 against the tension of a spring 58 connected to the arm 56 and to the under side of the motor board.

It may here be noted that the motor is stopped when the pin 52 is still in the cam track 53 as shown in Fig. 6. When the motor is again started, the gear 15 resumes its motion in the counter-clockwise direction as viewed from above, and the pin 52 rides inwardly against a cam fall 59 on the cam formation 54 and consequently the spring 58 swings the arm 56 inwardly, carrying with it the pin 52 and the player arm 43. This inward movement is sufficient to bring the player arm into a position above its initial playing position for the smallest record which, in the embodiment illustrated, is a ten-inch record.

The arm 56 is arrested by a projection 60 which may occupy a definite position for each size of record. Thus, in the embodiment illustrated, the projection 60 is arranged to have a position for a ten-inch record or for a twelve-inch record. In its twelve-inch position, the projection 60 is engaged by a surface 61 of the arm 56. In its ten-inch position, the projection 60 is engaged by a surface 62 on the arm 56. It will readily be understood that the arrestment of the arm 56 occurs at two different positions, depending upon the location of the projection 60.

The pin 52 is biased inwardly to a very limited degree by means of a light spring 63 on the arm 56. When the pin 52 rides inwardly on the cam fall 59, it engages an arcuate arm 64 which is pivotally mounted on the upper side of the gear 15 and is biased outwardly by a relatively weak spring 65 located on the other side of the pivot 53 from its major arcuate portion.

When the pin 52 rides inwardly over the cam fall 59, the pin moves the arcuate arm 64 inwardly against the tension of its spring 65, the spring 58 being much stronger than the spring 65. The spring 65 is, however, sufficiently strong to hold the spring 63 compressed after the arm 56 is arrested by the projection 60. While the pin 52 is still engaged by the arcuate arm 64 the player arm moves downwardly so as to bring the needle into engagement with the record. When the arm 64 clears the pin 52, the spring 63 moves the pin 52 inwardly to a very slight extent, so as to bring the needle into the first groove of the record. Thereafter, the gear 15 is arrested, leaving the pin 52 free to move inwardly with the player arm as the record is being played.

As has previously been noted, the gap 18 is opposite the pinion 14 during playing of a record. In order to connect the drive of the gear 15 to the pinion 14, I provide a bell crank lever 66 piv-

totally mounted in a radial slot 67 which slot is located adjacent the gap 18. The upwardly extending arm of the lever 66 is normally, that is, during playing of a record, engaged by a latch member 69 so that the horizontal arm of the lever 66 is held at a position above the large teeth 17 on the pinion 14.

When the latch member 69 is moved away from the vertical arm of the lever 66, the lever 66 swings downwardly, bringing the outer end of its major portion into alignment with the teeth 17. Engagement of the end of the lever 66 by the teeth 17 moves the gear 15 around sufficiently to bring the peripheral teeth of the gear into mesh with the pinion 14.

The latch 69 is pivotally mounted on the upper side of the gear 15 and is biased towards latching position by a spring 70. Means are provided for relatching the bell crank lever 66 during the single rotation of the gear 15. This means may suitably comprise an oblique flange 71 on the under side of the horizontal arm 51. It will be understood that during each revolution of the gear 15, the upwardly directed arm of the lever 66 is engaged by the flange 71 and is moved inwardly, thereby bringing the lever 66 into normal position in which it is again latched by the latch 69.

The latch 69 is released automatically by the player arm 43 at the end of the playing of a record. The arm 51 has a serrated edge 72 which is adapted, near the end of the playing of a record, to engage a dog 73 pivotally mounted on the latch member 69. The serrated edge 72 is adapted to slip past the dog 73 which is biased into a definite position by a spring 74.

When, however, a reverse movement is applied to the player arm 43, for example as the result of an eccentric end groove on the record, the serrated edge 72 canters the dog 73 and displaces the latch member 69 so that the lever 66 is released and the drive of the gear 15 is initiated.

The arm 51 also carries an abutment member 75 which is adapted to engage an abutment member 76 on the lever 66 and effect swinging movement of the latch member 69 as the result of the player arm moving inwardly to a sufficient extent upon the record. Thus, all modern types of records will control the trip mechanism and initiate the drive of the wheel 15.

The embodiment of the invention illustrated is provided with a single manual control and in its operation it is necessary merely to apply a record to the turntable and actuate this single manual control. The player arm then moves inwardly automatically, engages the record, and plays it, and after the playing of the record, the player arm rises and moves out clear of the record, whereupon the single control member is returned to initial position and the mechanism stops. It is then necessary to replace the record and again actuate the single control member.

In the present embodiment of the invention, the single control member is a button 77 which is located on the upper side of the motor board and is mounted through a slot 78 upon a bar 79 slidably mounted by means of studs and washers 80 on the under side of the motor board. The bar 79 carries the projection 60 previously mentioned. When the button 77 is moved forwardly, that is, to the ten-inch position, the projection 60 is set for the ten-inch position. When, however, the button 77 is moved rearwardly, or to the twelve-inch position, then the projection 60 is located in the twelve-inch position.

The bar 79 is provided with a pair of cam

members 82 defining a substantially V formation. In normal position, that is, when the bar 79 is "off" and is in its intermediate position, a pin 83 is located within the apex of the V formation 5 formed by the two cam members 82. This pin 83 is rigidly mounted upon the pawl 36 and projects downwardly through a suitable opening in the motor board into cooperative relation with the cam members 82.

It will readily be understood that when the bar 79 is displaced by the button 77 from its normal or intermediate position, the pin 83 is moved inwardly, that is, towards the center of the turntable from its position in Fig. 7. Consequently, 10 the pawl 36 is moved inwardly to withdraw the braking member 39 from the flange 25 of the turntable 13. Continued movement of the bar 79 moves tooth 35 of the pawl 36 away from the surface 34, and the spring 40, or the individual 15 spring of the lever 32, swings this lever in the counter-clockwise direction as viewed from above, about its pivot 33, thus permitting the spring 28 to move the idler 24 into contact with the driving wheel 23 and the flange 25 of the turntable 13. 20 When the button 77 is displaced from its normal 25 position to full extent, the pin 83 is located on flat surfaces 84 at the extremities of the cam members 82.

The bar 79 is biased towards its intermediate 30 or "off" position by means of a suitable spring. This spring may, for example, be a leaf spring 85, which may, if desired, be associated with a switch assembly 86. The spring 85 is adapted to cooperate with two adjacent pins 87 carried by 35 the bar 79. It will be understood that when the bar 79 is displaced from its normal position in either direction, the spring 85 bearing against one of the pins 87, tends to return the bar to its normal position. It will of course be understood 40 that any other desired type of spring may be employed for this purpose.

When the bar 79 is displaced to its full extent in either direction, it is held in such displaced position by means of a pin 88 which is adapted 45 to enter one or other of the two recesses 89 located in one side of the bar 79. The pin 88 is mounted on a bell crank lever 90 which is pivotally mounted at 91 upon the under side of the motor board 10. This bell crank lever is biased 50 by a spring 92 so that the pin 88 bears against the bar 79 and is adapted to enter the recess 89 which is presented to it by movement of the bar 79 in one direction or in the opposite direction. The recesses 89 are so conformed that the bar 79 55 is effectively held thereby until the pin 88 is again automatically withdrawn from the recess.

One end of the bell crank lever 90 carries a pin 93 which projects upwardly through a slot 94 in the motor board 10. The other end of the 60 bell crank lever carries an oblique flange which projects downwardly into operative relation with a peripheral cam formation 96 on the gear 15.

The flange 95 is engaged by the cam formation 96 during the rotation of the gear 15 with the 65 result that the pin 88 is withdrawn from the recess 89 in which it is located, thus freeing the bar 79 so that it is returned to its normal position by the spring 85. The movement of this bar actuates the switch assembly 86 in the manner which will hereinafter be described so that the motor stops.

The return of the bar 79 to normal position, permits the pin 83 to return to its position in the V formation between the cam members 82 under 70 the influence of the spring 40 so that the brake

is applied to the turntable. The actuation of the flange 85 by the cam formation 96 also throws the pin 83 towards the lever 32 so that this lever is positively swung so as to pull on the rod 31 and remove the idler 24 from the flange 25 and the driving wheel 23.

The cam formation 96 is sufficiently short to enable it to clear the flange 85 before the movement of the gear 15 is stopped. Consequently, the pin 83 is retracted from the lever 32 and this lever 32 tends to rotate in counter-clockwise direction as viewed from above, under the influence of the spring 40. This movement, however, brings the surface 34 of the lever 32 into engagement with the tooth 35 of the pawl 36 and the idler 24 is held clear of the wheel 23 and the flange 25, as shown in Fig. 7.

The switch structure 86 comprises two switches 87 connected in parallel in the circuit of the motor. Both switches are normally open. When, however, the bar 79 is displaced in one direction, one switch is closed, and when it is displaced in the other direction, the other switch is closed. It will, of course, be understood that any equivalent switch mechanism controlled by the bar 79, or an associated element, may be employed, if desired. In the switch illustrated, both switches 87 are constituted by leaves. The spring 85 is assembled between these switches and is adapted to actuate adjacent leaves by means of blocks 88 of suitable insulating material. It will readily be understood that when the spring 85 returns the bar 79 to its normal position, both switches 87 are opened.

The switches 79 are both arranged for late closing; that is, the switches 79 do not close until the pin 88 is almost on the point of dropping into one or other of the recesses 89. Consequently, when the bar 79 is displaced from normal position, the pawl 36 is moved outwardly to remove the braking member 39 out of contact with the flange 25 and the idler 24 engages the driving wheel 23 and the flange 25 before the pin 88 enters one of the recesses 89 and before the corresponding switch 79 becomes closed. This condition, which is illustrated in Fig. 10, prevents the idler 24 from being moved into contact with the driving wheel 23 when the latter is being driven at a high speed.

The operation is as follows:

When the phonograph is out of operation, the brake 39 is bearing against the flange 25, the idler 24 is clear of the flange 25 and the driving wheel 23, the player arm 43 is clear of the turntable and is elevated, the pin 48 resting upon the elevated portion of the cam 49, the cam formation 96 is clear of the flange 95 so that the pin 93 is clear of the lever 32, and the button 71 and bar 79 are at the intermediate or "off" position, both switches 79 being open.

To put the machine into operation, it is necessary to place a record upon the turntable. The button 71 is then moved to its operating position corresponding to the record to be played. If the record is a ten-inch record, the button 71 is moved forwardly; if it is a twelve-inch record, the button 71 is moved rearwardly. The resulting movement of the bar 79 locates the projection 60 in the ten or twelve inch position, so that it is adapted to be engaged by the surface 62 or the surface 61, as the case may be, of the arm 56.

The movement of the bar 79 actuates the pin 83 and swings the pawl 36 inwardly towards the center of the turntable, removing the brake 39 from the turntable and removing the tooth 35

out of contact with the face 34 of the lever 32.

The spring 40 moves the lever 32 in counter-clockwise direction as viewed from above, and moves the rod 31 towards the idler 24. The idler is caused to contact the wheel 23 and the flange 25 of the turntable. The pin 88 becomes located on one of the surfaces 84 and the bar 79 is locked in its displaced position by the entry of the pin 88 into one or other of the recesses 89, depending upon the direction in which the bar 79 was moved. The final part of the movement of the bar 79 closes the corresponding switch 87.

The operation of the motor through the wheel 23 and idler 24 drives the turntable. The gear 15 is initially in its position of Figs. 4 and 6 and is in mesh with the pinion 14 which is driven by the turntable and consequently the gear 15 is driven immediately the motor is put into operation. The arm 56 is in its outermost position since the pin 52 is in the cam track 53. The rotation of the gear 15 brings the fall 59 of the cam 54 past the pin 52 so that the spring 40 moves the player arm inwardly.

During its inward movement, the pin 52 engages the arcuate arm 64 but the strong spring 58 moves the arm 64 inwardly until its surface 61 or surface 62 engages the projection 60, thus locating the player arm in elevated condition above the initial playing position for the size of record on the turntable. The fall 50' of the cam 49 now passes below the pin 48, with the result that the player arm is caused to drop downwardly to bring its needle into engagement with the record. Thereafter the arcuate arm 64 clears the pin 52 and the spring 63 gently moves the player arm inwardly to a slight extent so as to cause the needle to enter the first groove of the record.

During the rotation of the gear 15, the upwardly directed arm of the lever 66 has been moved inwardly by the cam formation 71 on the arm 51 so that the lever 66 is elevated clear of the large teeth 17 on the pinion 14. Consequently, when the gap 18 becomes aligned with the pinion 14, the drive of the cam 15 is terminated. At this time the detent 19 enters the recess 21 in the gear 15 so that the gear is held immovable until the drive of the gear is again initiated.

The record is now played, the player arm moving in gradually over the surface of the record. At the end of the playing, the latch 69 is released by the action of the serrated member 72 and the dog 73 or by the action of the abutment member 75 and the abutment member 76. The horizontal portion of the lever 66 now drops into the path of the large teeth 17, with the result that the gear 15 is moved to a slight extent and is brought into mesh with the pinion 14.

The rise 50 of the cam 49 now passes below the pin 48 so that the player arm 43 is elevated. The pin 52 is then engaged by rise 55 of the cam 54 and swung outwardly, carrying the player arm outwardly, clear of the record, and carrying the arm 56 outwardly against the tension of the spring 58. The cam formation 96 now rides over the flange 95 on the bell crank lever 90, swinging this lever against the action of the spring 92.

The movement of the lever 90 carries the pin 93 into engagement with the lever 32 so that the idler 24 is pulled by the rod 31 away from flange 25 and driving wheel 23. The movement of the lever 20 withdraws the pin 88 from the recess 89 in which it was located, so that the spring 85 moves the bar 79 into its intermediate position.

opening that switch 97 which was closed, and terminating the drive of the motor.

The return of the bar 79 to its intermediate position, enables the spring 40 to return the braking element 39 into contact with the flange 25. At this time the cam formation 36 clears the flange 95 so that the lever 98 is swung by the spring 92 until the pin 88 engages the side of the bar 79 between the two recesses 89. The movement of the pin 88 away from the lever 32 enables the spring 40 to move this lever to bring the surface 34 into engagement with the tooth 35 of the pawl 36, as shown in Fig. 7. This relation maintains the idler 24 clear of the driving wheel 23 and flange 25 of the turntable. This movement of the lever 98 brings the pin 88 clear of the lever 32, as shown in Fig. 7, so that this lever is free to move under the influence of the spring 40 just as soon as the bar 79 is moved sufficiently in one direction or the other to swing the pawl 36 away from surface 34 of the lever 32. After the motor and the turntable have stopped and the bar 79 has returned to its intermediate or "off" position, the machine is again in the position described at the beginning of this description of the operation.

Although the invention has been described in connection with the specific details of a preferred embodiment thereof, it must be understood that such details are not intended to be limitative of the invention except in so far as set forth in the accompanying claims.

Having thus described our invention, we declare that what we claim is:

1. A phonograph comprising a turntable, a player arm, mechanical means for driving the turntable, means for operatively connecting and disconnecting said mechanical drive means, automatic means operable by said drive means for moving the player arm clear of the turntable after the playing of a record, trip means controlled by the player arm for initiating the operation of said automatic means at the end of the playing of a record, and means for operating said connecting and disconnecting means to disconnected position when the player arm is moved to a position adjacent its initial playing position to arrest the turntable and the player arm in a position adjacent its initial playing position.

2. A phonograph comprising a turntable, a player arm, mechanical means for driving the turntable, means for operatively connecting and disconnecting said mechanical drive means, automatic means operable by said drive means for moving the player arm clear of the turntable after the playing of a record and back to initial playing position, trip means controlled by the player arm for initiating the operation of said automatic means at the end of the playing of a record, means for operating said connecting and disconnecting means to disconnected position when the player arm is moved to a position clear of the turntable to arrest the turntable and the player arm in a position clear of the turntable, and manually operable means for moving said connecting and disconnecting means to connected position whereby the drive of the turntable and said automatic means is resumed to bring the player arm into initial playing position.

3. A phonograph comprising a turntable, a player arm, mechanical means for driving the turntable, means for operatively connecting and disconnecting said mechanical drive means, brake means for said turntable, automatic means operable by said drive means for moving the player

arm clear of the turntable after the playing of a record, trip means controlled by the player arm for initiating the operation of said automatic means at the end of the playing of a record, and means for applying said brake means and for operating said connecting and disconnecting means to disconnected position when the player arm is moved to a position clear of the turntable to arrest the turntable and the player arm in a position clear of the turntable.

4. A phonograph comprising a turntable, a player arm, mechanical means for driving the turntable, means for operatively connecting and disconnecting said mechanical drive means, brake means for said turntable, automatic means operable by said drive means for moving the player arm clear of the turntable after the playing of a record and back to initial playing position, trip means controlled by the player arm for initiating the operation of said automatic means at the end of the playing of a record, means for applying said brake means and for operating said connecting and disconnecting means to disconnected position when the player arm is moved to a position clear of the turntable to arrest the turntable and the player arm in a position clear of the turntable, and manually operable means for rendering said brake means inoperative, for moving said connecting and disconnecting means to connected position whereby the drive of the turntable and said automatic means is resumed to bring the player arm into initial playing position.

5. A phonograph comprising a turntable, a player arm, mechanical means for driving the turntable, means for operatively connecting and disconnecting said mechanical drive means, brake means for said turntable, automatic means operable by said drive means for moving the player arm clear of the turntable after the playing of a record and back to initial playing position, trip means controlled by the player arm for initiating the operation of said automatic means at the end of the playing of a record, means arranged to be moved into either of two positions to determine the initial playing position of the player arm for records of either of two sizes, means for applying said brake means and for operating said connecting and disconnecting means to disconnected position when the player arm is moved to a position clear of the turntable to arrest the turntable and the player arm in a position clear of the turntable, and manually operable means for moving said movable means into a selected one of two said positions, for rendering said brake means inoperative, and for moving said connecting and disconnecting means to connected position whereby the drive of the turntable and said automatic means is resumed to bring the player arm into the selected playing position.

6. A phonograph comprising a turntable, a player arm, a motor having a driving element, an idler movable into and out of engagement with said driving element and said turntable, brake means for said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means

after the return of the player arm to initial playing position, and means operably connected to first said automatic means for applying the brake and for effecting the movement of said idler out of engagement with said driving element and said turntable when the player arm is clear of the turntable.

7. A phonograph comprising a turntable, a player arm, a motor having a driving element, an idler movable into and out of engagement with said driving element and said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, means operably connected to first said automatic means for effecting the movement of said idler out of engagement with said driving element and said turntable when the player arm is clear of the turntable, and manual means for effecting reengagement of the idler with said driving element and said turntable.

8. A phonograph comprising a turntable, a player arm, a motor having a driving element, a switch controlling said motor, an idler movable into and out of engagement with said driving element and said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, and means operably connected to first said automatic means for effecting the movement of said idler out of engagement with said driving element and said turntable and for opening said switch when the player arm is clear of the turntable.

9. A phonograph comprising a turntable, a player arm, a motor having a driving element, a switch controlling said motor, an idler movable into and out of engagement with said driving element and said turntable, brake means for said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, and means operably connected to first said automatic means for applying said brake and for effecting the movement of said idler out of engagement with said driving element and said turntable and for opening said switch when the player arm is clear of the turntable.

10. A phonograph comprising a turntable, a player arm, a motor having a driving element, a switch adapted to control said motor, an idler

movable into and out of engagement with said driving element and said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, means operably connected to first said automatic means for effecting the movement of said idler out of engagement with said driving element and said turntable and for opening said switch when the player arm is clear of the turntable, and manual means for effecting reengagement of the idler with said driving element and said turntable and for closing said switch.

11. A phonograph comprising a turntable, a player arm, a motor having a driving element, a switch adapted to control said motor, an idler movable into and out of engagement with said driving element and said turntable, brake means for said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, means operably connected to first said automatic means for applying said brake means and for effecting the movement of said idler out of engagement with said driving element and said turntable and for opening the switch when the player arm is clear of the turntable, and manual means for rendering said brake means inoperative and for effecting reengagement of the idler with the driving element and said turntable and for closing said switch.

12. A phonograph comprising a turntable, a player arm, a motor having a driving element, switch means controlling said motor, an idler movable into and out of engagement with said driving element and said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, means adjustable to a plurality of positions to determine said initial playing position for records of different sizes, means operably connected to first said automatic means for effecting the movement of said idler out of engagement with said driving element and said turntable and for opening said switch means when the player arm is clear of the turntable, and manual means selectively and manually movable to a plurality of positions for moving said adjustable means to a position for a selected initial playing position, for effecting reengagement of the idler with said driving ele-

ment and said turntable, and for closing said switch means.

13. A phonograph comprising a turntable, a player arm, a motor having a driving element, switch means controlling said motor, an idler movable into and out of engagement with said driving element and said turntable, brake means for said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, means adjustable to a plurality of positions to determine said initial playing position for records of different sizes, means operably connected to first said automatic means for applying said brake means, for effecting the movement of said idler out of engagement with said driving element and said turntable, and for opening said switch means when the player arm is clear of the turntable, and manual means selectively and manually movable to a plurality of positions for moving said adjustable means to a position for a selected initial playing position, for rendering said brake means inoperative, for effecting re-engagement of the idler with said driving element and said turntable, and for closing said switch means.

14. A phonograph comprising a turntable, a player arm, a motor having a driving element, switch means controlling said motor, an idler movable into and out of engagement with said driving element and said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, a member manually adjustable into a plurality of adjusted positions, means biasing said member to a normal position, means operatively associated with said member to determine in said adjusted positions the initial playing position for records of different sizes, said switch means being operatively associated with said manually adjustable member whereby said switch means are closed when said member is in any of its adjusted positions and open when said member is in its normal position, means for holding said member in any of its adjusted positions, means operably connected to first said automatic means for effecting movement of said idler out of engagement with said driving element and said turntable and for releasing said holding means when the player arm is clear of the turntable, last said means and said manually adjustable member being interconnected whereby the displacement of said member from normal into any of its adjusted positions controls the engagement of said idler with said driving element and said turntable.

15. A phonograph comprising a turntable, a player arm, a motor having a driving element,

switch means controlling said motor, an idler movable into and out of engagement with said driving element and said turntable, brake means for said turntable, automatic means for moving the player arm clear of the turntable after the playing of a record and back to initial playing position, means for connecting and disconnecting said automatic means to and from said turntable, trip means controlled by the player arm for connecting last said connecting and disconnecting means at the end of the playing of a record, automatic means for disconnecting last said connecting and disconnecting means after the return of the player arm to initial playing position, a member manually adjustable into a plurality of adjusted positions, means biasing said member to a normal position, means operatively associated with said member to determine in said adjusted positions the initial playing position for records of different sizes, said switch means being operatively associated with said manually adjustable member whereby said switch means are closed when said member is in any of its adjusted positions and open when said member is in its normal position, means for holding said member in any of its adjusted positions, means operatively connected to first said automatic means for effecting movement of said idler out of engagement with said driving element and said turntable, for applying said braking means, and for releasing said holding means when the player arm is clear of the turntable, last said means and said manually adjustable member being interconnected whereby the displacement of said member from normal into any of its adjusted positions renders said brake means inoperative and controls the engagement of the idler with said driving element and said turntable.

16. In a phonograph comprising a turntable, a motor for operating said table, and a player arm, in combination, a slidable member having a normal position and adapted to be moved oppositely into two controlling positions, means controlled by said slidable member for determining the initial playing position of the player arm, means for holding said slidable member in either of said controlling positions, means controlled by the player arm for releasing said holding means, means normally biasing said slidable member to normal position, and switch means for said motor controlled by said slidable member adapted to be closed in either of said controlling positions and opened in said normal position.

17. In a phonograph having a turntable, a motor controlling the turntable, a player arm and automatic means for moving the player arm outwardly beyond a played record and inwardly to initial playing position, in combination, switch means controlling the operation of the motor, a slidable member including abutment means for determining the initial playing position of the player arm, means biasing said slidable member to a normal position, means for holding said slidable member in a plurality of operative positions, means controlled by the player arm for releasing said holding means, and means operatively connecting said slidable member to said switch means whereby said switch means is closed by said slidable member in any of its operative positions and is opened by said slidable member in moving towards its normal position.
